DESIGN FOR A DISPLAY STAND FOR ILLUSTRATED POSTAL CARDS

Edward Olszewski, Detroit, Mich.

Application October 13, 1943, Serial No. 111,348

Term of patent 14 years

To all whom it may concern:

Be it known that I, Edward Olszewski, a citizen of the United States, residing in the city of Detroit, county of Wayne, and State of Michigan, have invented a new, original, and ornamental Design for Display Stands for Illustrated Postal Cards, of which the following is a specification, reference being had to the accompanying drawing, forming a part thereof.

Fig. 1 is a perspective view of a display stand for illustrated postal cards, showing my new design;

Fig. 2 is a side elevational view, on an enlarged scale; and

Fig. 3 is a top plan view, also on an enlarged scale.

I claim:

The ornamental design for a display stand for illustrated postal cards, as shown.

EDWARD OLSZEWSKI.
